UNITED STATES PATENT OFFICE.

WILLIAM PRELLWITZ, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed September 11, 1923. Serial No. 662,035.

To all whom it may concern:

Be it known that I, WILLIAM PRELLWITZ, a citizen of the United States, and a resident of Easton, county of Northampton, and State of Pennsylvania, have invented a certain Steel Retainer, of which the following is a specification, accompanied by drawings.

The invention relates to rock drills, but 10 more particularly to drill steel retainers.

One object of the invention is to produce a drill steel retainer which is strong and rugged, but also adequately cushioned by suitable springs which take up the shock of 15 the impact of the collar of the drill steel against the retainer and also serve to maintain the retainer centered on its supporting and guiding members.

Another object of the invention is to enable the retainer to be pivotally hung and adjusted on the front head in a simple and convenient manner which reduces the number parts required and prevents the retainer from springing outwardly, due to the jar 25 imparted by the drill steel.

A further object is to secure means affording a stop or bearing for the retainer against the front head, so that the retainer does not bear directly against the shank of 30 the drill steel, thus leaving the drill steel free to rotate as required.

Further objects will hereinafter appear, and the invention is shown in one of its preferred forms in the drawings, in which 35

Figure 1 is a longitudinal section in elevation of the front end portion of a rock drill.

Figure 2 is a view similar to Figure 1 showing the position the parts assume when 40 the drill steel is pulled out of a hole.

Figure 3 is a transverse section taken on the line 3—3 of Figure 1 looking in the direction of the arrows.

Figure 4 is a perspective view of the retainer, and

Figure 5 is an end elevation of the retainer.

Referring to the drawings, only so much of a rock drill is shown as will serve to illustrate the invention, and in this instance, the front end portion of the rock drill comprises the front head A, spaced from the cylinder B by the front cylinder washer C

and connected thereto by the usual side rods, not shown.

Disposed within the cylinder B is a piston D having a fluted forward extension E, said extension being adapted to reciprocate within a chuck F to deliver impact blows upon a hollow drill steel G supported within the chuck.

In accordance with the present invention, the front head A is formed with an upper recess J and an opposed lower recess K. A flange H of the front cylinder washer C forms a closure of one end of the recess J. A plunger L having a grooved head O is slidably disposed in the recess J and a coil spring P urges the plunger L outwardly from the recess J.

A bearing head S movable in the recess K has a stem Q slideable in the hole R in the front head A and the head S is formed with a groove T and a notch U. A coil spring X, one end of which bears against the head S is under constant compression for holding the head S in its outward position, and for cushioning the retainer. An auxiliary heavier spring W which is not under compression normally bears against the shoulder V under the head S. The outer spring X is more flexible than the inner spring W and compresses more rapidly in the downward movement of the head S. The outer spring X effects the locking of the retainer in proper operative position and takes the jar of the downward pull of the retainer. The center spring W may be added to further take the shock after the outer spring X has been compressed to a certain degree, so that the head S may be brought to a stop against the tension of the inner spring.

The steel retainer Y comprises side arms Z which are connected at their lower ends by the yoke a and at their outer ends by the wedge shaped cross piece b. The side arms Z are bowed at a in order to embrace and bear against the front head A and permit the yoke a to encircle the steel G but without touching the steel. The retainer stops against the front head A as shown in Figure 3 so that the drill steel is free to rotate. The yoke a is formed with a shoulder d, which is adapted to receive the collar e of the drill steel G. The wedge shaped piece b is interposed between the plunger L

and the bearing head S, and has bearing both in the grooved head O of the plunger L and in the groove T of the head S. The springs P and X, and W cooperate to force 5 the wedge shaped connecting piece b toward the bottom of the groove T, so as to hold the yoke around the drill steel G as shown in Figure 2. Whenever it is desired to insert the drill steel G in the chuck F or re- 10 move it therefrom, the arms Z may be moved outwardly so that the wedge shaped piece b will catch in the notch U of the head S which will hold the arms of the retainer in their outward position, as shown in dot 15 and dash lines in Figure 1.

Movement of the collar e of the drill steel G will not be permitted beyond the shoulder d of the retainer, because, in the event of any force being exerted on the collar e, 20 the yoke a will press more tightly against the front head A, due to the restraint exerted on the wedge shaped piece b by the groove T, and because the bearing edge of the wedge shaped piece b lies outwardly be- 25 yond the longitudinal axis of the bearing members or heads O and S. Whenever the springs X and W are compressed, due to the tendency of the drill steel G to move outwardly from the chuck F, the plunger L 30 will follow up the wedge shaped piece b, due to the expansion of the coil spring P, and thus serve to guide the wedge shaped piece in its return movement. The wall of the recess K is provided with a groove K' 35 to permit the downward movement of the wedge shaped piece b.

In order to guard against excessive shocks and strains to the springs W and X, the bottom of the groove K' is arranged 40 with definite relation to the normal position of the wedge b and serves as a stop for the wedge in one direction. By thus limiting the downward movement of the yoke, the springs are protected against complete 45 compression and as a result, the frequent breakage of springs and resulting delays in drilling are eliminated.

I claim:

1. In a steel retainer for rock drills, the 50 combination of a front head having a single forward recess and a single rearward recess, a drill steel supported by the front head, a yoke pivoted on one side of the front head for retaining the steel within the front head, said yoke being provided with a single

cross piece, connecting the sides of the yoke, a grooved bearing head arranged slidably within the forward recess to support the yoke, a plurality of springs to support the bearing head, and a spring pressed 60 plunger having a concave face cooperating with the cross piece to hold the yoke in retaining and releasing position.

2. In a steel retainer for rock drills, the combination of a front head having a single forward recess and a single rearward recess, 65 a drill steel supported by the front head, an endless yoke for retaining the steel within the front head comprising bowed arms to embrace the front head and a cross piece to connect the arms, said yoke being pivoted to one side of the longitudinal axis of the machine, a bearing head having a groove to support the yoke in retaining position and a notch to support the yoke in releasing position, said bearing head being arranged within the forward recess, 70 a plurality of springs to support the bearing head and absorb the blow of the steel against the yoke, and a spring pressed plunger having a concave face to cooperate 75 with the cross piece for holding the yoke in retaining and releasing position.

3. In a steel retainer for rock drills, the combination of a front head having a single forward recess and a single rearward recess, 80 a drill steel supported by the front head, an endless yoke retaining the steel within the front head comprising a pair of arms to embrace the front head and a cross piece 85 formed integral with the arms to provide a single bearing for said yoke, said yoke being pivoted to one side of the longitudinal axis of the machine, a bearing head in said forward recess to support the yoke, said bearing head having a groove and a notch in one face 90 to support the yoke in retaining and releasing positions, a plurality of springs in the forward recess to absorb the blow of the drill steel against the yoke, a spring pressed plunger in the rearward recess, said plunger having a concave face to cooperate with the cross piece for holding the yoke in retaining 95 and releasing positions, and a stop for limiting the movement of the yoke in one direction.

In testimony whereof I have signed this specification.

WILLIAM PRELLWITZ.
